M. REED

ROBE

Filed Sept. 23, 1924

Inventor
May Reed.

By *George A. O'Brien*
Attorney

UNITED STATES PATENT OFFICE.

MAY REED, OF MONROVIA, CALIFORNIA.

ROBE.

Application filed September 28, 1924. Serial No. 739,365.

To all whom it may concern:

Be it known that I, MAY REED, a citizen of the United States, residing at Monrovia, in the county of Los Angeles and State of California, have invented certain new and useful Improvements in Robes, of which the following is a specification.

This invention relates to an improved robe, which has been especially, but not necessarily designed for use by automobile occupants.

This contrivance has been devised with a view to affording a comfort producing article of apparel to protect the wearer's feet and legs from the cold.

In carrying out the above end, I provide a novel robe, which embodies a pocket into which the feet and lower legs are placed, together with a flap which is adapted to extend up and over the lap of the wearer.

An important feature is the construction of the pocket wherein the end walls are constructed to facilitate insertion of the feet, but are capable of being folded over the lower front of the pocket, to wrap it tightly about the feet and legs.

Other feature and advantages of the invention will become apparent from the following description and drawing.

30 In the accompanying drawing, forming a part of this application, and in which like numerals are employed to designate like parts throughout the same:

35 Figure 1 is a top plan view of a robe constructed in accordance with this invention.

Figure 2 is a bottom plan view.

Figure 3 is a view like Figure 2, showing the lower portion thereof, with the pocket partially expanded.

40 As before indicated, the improved article comprises chiefly a pocket 1 at its lower end adapted for reception of the feet and lower portions of the legs, and a flap 2, which is adapted to extend over the lap of the wearer. Altho, the device can be constructed otherwise, it is preferably formed from three pieces of material. The main piece is a relatively long and rectangular strip 3 which has its lower end turned in and under at 4, to provide the under wall of the pocket. The pocket is completed, through the provision of a pair of substantially triangular pieces of material 5, which are stitched as at 6 to the edges of the doubled lower end portion of the strip 3. The

top edges of the triangular pieces 5 and the marginal edges of the piece 3 are provided with a suitable binder 7, which serves to render the device strong and durable. The pocket is substantially V-shaped when opened, and the feet may be readily inserted into it. Its depth is approximately equal to one-half the length of the device, although these proportions may well be varied. That part extending above the pocket constitutes the aforesaid flap, and the flap may well be folded upon the lines 8 (see Figure 1).

After the feet have been placed into the pocket, the end walls are folded in half and the halves then folded inwardly toward each other over the front lower portion of the pocket, as seen in Figure 1. Such folding of the end wall serves to wrap the feet and legs in the pocket to insure warmth. For maintaining the same in this folded state, I provide triangular end pieces, with snap fasteners having hooks, which may be secured in place in any manner, the same being adapted to be hooked into the adjacent rings 10 carried by the strap 11, stitched or otherwise fastened to the front of the pocket.

45 In practice, the pocket 1 is opened somewhat as shown in Figure 3 and the feet are inserted into the same. As before stated, this figure shows the under side of the pocket, that is, the side which is next to the floor board. After the feet have been inserted, the triangular end walls of the pockets are folded in half and then folded upwardly and over the front side of the pocket as indicated in Figure 1. The snap hooks are then engaged with the eyes 10 to maintain the pocket closed and well wrapped around the feet. The flap 2 is drawn up over the lap to act somewhat in the manner of the ordinary lap robe. In constructing the device, any appropriate material may be utilized, and although it is not essential, an appropriate lining may be provided to insure warmth and to intercept the passage of cold air. To make the device more sturdy the binder may be of leather. Likewise, the rings 10 may be of leather and may be engraved or otherwise provided with the owner's initials.

50 I claim:

1. A robe of the type specified comprising an open top substantially V-shaped pocket having triangular end walls, said end walls being adapted to be folded into

halves and the halves being adapted to be folded inwardly toward each other and over the top side of the pocket, so as to lap the pocket around the wearer's legs and feet, and 5 anchoring rings attached to the top sides of the pockets, fasteners carried by the central portions of said end walls and adapted to be engaged with said rings, and a lap covering flap integral with and extending in a 10 plane from the top wall of said pocket.

2. A robe of the class described formed from an elongated substantially oblong piece of material folded upwardly upon itself at the lower end to provide the opposed walls of an extensible pocket, and a lap covering 15 flap extending from the top wall of the pocket, and a pair of substantially triangular pieces of material stitched to the edges of the pocket wall to complete the pocket, said end walls being adapted to be folded 20 into halves, and the halves being adapted to be folded over the top wall of the pocket, so that the feet and legs may be wrapped in said pocket, with said flap extending up and over the lap of the wearer. 25

In testimony whereof I affix my signature.

MAY REED.
